SHOWER BATH CABINET

Paul W. Kerr, Elkhart, Ind., assignor to Henry Weis Manufacturing Company, Inc., Elkhart, Ind.

Original application October 5, 1936, Serial No. 103,965. Divided and this application January 12, 1939, Serial No. 250,487

6 Claims. (Cl. 189—2)

This invention relates to shower bath cabinets, and among other objects aims to provide a leak-proof knock-down sheet metal shower cabinet which can be produced at lower cost than heretofore and will have a quality and decorative appearance in harmony with standard bath room design.

The nature of the invention may be readily understood by reference to one construction embodying the invention and illustrated in the accompanying drawings.

In said drawings:

Fig. 1 is a perspective view of a shower cabinet;

Fig. 2 is a vertical section of a detail taken on the plane 2—2 of Fig. 1;

Fig. 3 is a vertical section above the entrance to the cabinet and taken on the plane 3—3 of Fig. 1;

Fig. 4 is a plan section on an enlarged scale taken through a corner of the cabinet on the plane 4—4 of Fig. 1;

Fig. 5 is a vertical section through the corner construction taken on the plane 5—5 of Fig. 4;

Fig. 6 is a vertical section taken on the plane 6—6 of Fig. 4;

Fig. 7 is a vertical section through the door sill taken on the plane 7—7 of Fig. 1;

Fig. 8 is a vertical section through the base of the cabinet taken on the plane 8—8 of Fig. 1;

Fig. 9 is a plan view of the receptor bottom; and

Fig. 10 is a fragmentary sectional view illustrating a form of door frame construction which may be employed if the front of the cabinet be faced by conventional wall surfacing such as plaster or tile. The section corresponds to the plane 10—10 of Fig. 1.

Knock-down sheet metal shower cabinets possess many advantages over the conventional built-in shower cabinets characterized by marble or other slab side walls and terrazzo or similar receptors. To be acceptable as equipment for the better classes of bathrooms, such sheet metal cabinets must harmonize with standard bathroom design. The illustrative shower cabinet possesses all the advantages inherent in knock-down sheet metal shower cabinets; yet its design is such as to render it capable for use as equipment in the highest class of installations.

As here shown, the shower bath cabinet comprises the receptor 10 forming the floor of the cabinet, and sheet metal side wall sections 11 forming the cabinet enclosure except for the doorway 12. The latter may be closed either by

a curtain or door, as desired. The receptor advantageously rests upon a base 13, whose height is preferably sufficient to accommodate both the dish of the receptor bottom 14 and the drain outlet fixture 15, which is connected to the receptor bottom at its lowest point. The base 13 is here shown of channel section and the receptor is centered thereon by downwardly projecting brackets 16 welded or brazed as at 17 to the bottom of the receptor. An outwardly bent resilient tongue 18 struck from the bracket is adapted to spring under the upper edge 19 of the base when the receptor is seated to lock the latter to the base.

Both the side walls and the receptor are designed to be finished in porcelain or other enamel, preferably to harmonize in color with the other bathroom fixtures. Porcelain enamel is preferably used for the better grade of cabinets, since this is a standard finish for other bathroom fixtures. It has not been practicable heretofore to employ porcelain enamel on sheet metal shower cabinets. The firing of the enamel caused warping of the edge of the sheets and it was impossible to form leak-proof joints between the various sections of the cabinet to say nothing of chipping and cracking of the enamel in assembling a cabinet. The present construction provides a shower cabinet quite as leak-proof as ordinary shower cabinets and at the same time possesses quality and finish comparable to other standard bathroom fixtures.

Both the receptor and side walls are formed of sheet enamelling iron or steel, 16 to 14 gauge metal being satisfactory for a receptor and a somewhat lighter gauge, 20 to 16 gauge, being satisfactory for the side walls. The side walls are here shown formed in three sections, namely, two side sections 20 and a back section 21. The side sections are here shown including the front wall portions 22, which are formed to provide the side stiles 23 of the door opening. To facilitate coating with porcelain enamel, it is sometimes desirable to make separate front, side and rear sections,—in which event each vertical corner will be provided with a common joint.

The sheet metal side walls are preferably finished by an enamel coating of an appropriate color. For the better grades of cabinets, the coating is vitreous porcelain enamel or its equivalent which may be applied to advantage by the so-called wet process. In this process, a ground or grip coat is sprayed or otherwise applied to the sheet metal surfaces and either dried at room temperatures or in a drying oven for about an

hour and a half at a temperature of about 150° F. The ground coat is then burned or fired in an enamelling oven for about six minutes at about 1550° F.

All margins, inside and out, of the side walls are preferably coated with so-called flexible enamel which, at the present time, is available only in dark colors. Black is preferably employed since it can be so used as to have a decorative effect. The marginal black stripes are preferably wider than the margin covered by the corner structure, to leave a narrower stripe of about $\frac{1}{8}$ of an inch visible. The visible portion of the black stripe thus has a decorative effect. After drying, the enamelled margins are burned at about 1550° F.

Thereafter, the color or finish coats (in this case two coats) are applied by spraying or otherwise applying enamel material which will burn to the desired color. Preferably the coats are each successively dried and fired. This insures that the final or top coat will obliterate any imperfections in the underlying coat. After drying and before firing, the finish coatings are removed along the margins so as to leave a uniform width of black margin visible. To fire the enamel, the articles are placed in an enamelling oven and subjected to temperatures of about 1600° F. for about six minutes. The greater flexibility of the black enamel on the margins allows the latter to flex slightly without danger of breaking or cracking the enamel finish.

The lower margins of the side walls are bent inwardly as at 24 and terminate with a downwardly projecting flange 25, which is seated in a frame 26 embracing the upper edge 27 of the receptor side walls 28 (see Fig. 6). Frame 26 is advantageously of sheet metal formed to provide a channel 29 for the side wall flange 25, and another channel 30 for fitting over the receptor side walls. The margin 27 of the receptor side walls is preferably offset inwardly so that the outer face 31 of the frame is flush with the outer face of the receptor side wall 28. The frame is here shown provided with an inwardly bent terminal flange 32 which rests upon the offset 33 of the receptor. The channel 29 in the frame is advantageously filled with a plastic cement 34 or plastic caulking compound which flows around the flange 25 when it is inserted in the channel and serves to seal the channel against the entrance of moisture.

A door sill 35 covers that portion of the frame 26 which extends across the doorway. The sill is provided with a downwardly projecting flange 36 which is seated in the channel 29. Downwardly projecting end flanges 37 carried by the sill are connected by bolts or rivets 38 to the stile faces 23. The inner edge of the sill is finished by a downwardly extending flange 39.

As here shown, the joints between adjacent side wall sections are located at the corners of the cabinet. The adjacent margins 40 of the side wall sections (see Fig. 4) are inwardly offset at 41, and the space 42 between them is spanned by a corner strip 43, which extends across the margins 40 and is provided with outwardly bent side margins 44 extending behind the offsets 41 to prevent the separation or displacement of the side wall margins. Gaskets 45 of semi-plastic material serve to seal the joint between the side wall margins and the corner strip 43. The gaskets are clamped between the side wall margins and the corner strip 43 by an outer corner member 46, whose flanges 47 lie behind and engage

the side wall flanges, and which is drawn toward the corner strip by clamping means. The clamping means are here shown in the form of hook-shaped cam lugs 48 carried by the corner strip 43 and a slotted locking strip 49 associated with the outer corner member. In the present case, the corner member 46, which is made of relatively thin sheet metal, carries a slotted corner bar 50 whose side margins 51 extend under the folded over flanges 47 of the corner member. The slots 52 in the bar 50 are of sufficient length to admit the lugs 48, and when the latter have been passed through the slots, they are engaged by the slotted locking strip 49 which acts against the inclined or beveled faces 53 of the lugs 48 to create the aforesaid clamping action between the corner strip 43 and the outer corner member 46. To apply the corner strip 43, the locking strip 49 is moved so that its slots 54 register with the slots 52 in the corner bar. After the lugs 48 have been passed through the registered slots, the locking strip 49 may be driven down from the top of the cabinet to create the aforesaid clamping action.

Clamping pressure is maintained not only by the resilience of the cover strip 43 and the bar 50 but by that of the side wall margins 40 which are generally slightly warped in firing. The flexible black enamel on these margins allows flexure thereof under the clamping action without danger of cracking or chipping of the enamel. The soft gaskets 45 compensate for any inequalities which might occur and also obviate the necessity for excessive clamping pressure. By these means the joints are not only initially rendered leak-proof but, what is more important, are maintained leak-proof throughout the life of the cabinet.

The corner bar 50 terminates short of the bottom of the corner member 46 to accommodate a bottom fitting 55 (see Fig. 5) which is inserted under the folded over flanges 47 and is connected to the corner member 46 in any appropriate way such as welding or by prick-punching the flanges 47 into the metal of the fitting. The latter is inwardly directed as at 56 and provided with a downwardly extending angular flange 57 (in alignment with the flanges 25) which is seated in the channel 29 across the corner of the receptor. The inwardly offset portions 56 of the member 55 are overlapped by the ends 58 (Fig. 4) of the offset portions 24 of the side walls. Preferably such ends are upwardly and inwardly offset as at 59 (Figs. 4 and 6) by an amount equal to the thickness of the inwardly directed portion 56 and flange 57. The overlapping of the bottom fitting 55 by the side margins of the side walls, as aforesaid, avoids the possibility of any leakage at this point. It should be understood, however, that this joint is not directly exposed to water. Only condensation is likely to reach the space behind the corner strip 43 and this runs down and into the receptor with no tendency to travel laterally.

The corner strips 43 are advantageously provided with locking members in the form of hooks 60 which engage the under face of the offset portions 33 of the receptor, thereby firmly locking the cabinet side walls to the receptor.

The upper edge of the cabinet is advantageously finished by a frame 61 formed with a channel 62 fitting over the upper edge of the side walls and an inwardly extending molding 63 of rectangular section. If desired, a sheet metal top 64 may be placed upon the molding 63 and con-

nected to its flanges 65 by screws 66. The upper edges of the side walls are preferably notched as at 67 at a plurality of points (see Figs. 2 and 3), so that, if desired, wood screws 68 or the like may be driven through the frame 61 into the building walls, without requiring the drilling of the metal of the side walls. Such notched portions 67 are concealed by the channel 62 of the frame. Preferably, the metal of the frame indented or otherwise marked at points 69 in registry with the notches, so that the metal may be drilled at the proper points if it be desired to employ anchoring screws 68. The screws would be hidden from below by the molding 63 even if no top 64 were used.

The top 64 is advantageously provided with a marginal flange 70 spaced from the front and side walls a distance equivalent to the thickness of the conventional wall plaster or other wall surfacing. If it be desired to extend curtain walls from the upper edges of the cabinet to the ceiling of the room, this can be easily done by attaching metal or other lath 71 to the flanges 70 of the top (which are preferably perforated as at 72 for this purpose). The lath may, thereupon, be coated with plaster 73 flush with the face of the cabinet.

The lintel 74 extending across the door opening is provided with flanges 75 bolted or otherwise connected to the faces of the stiles. The front face 76 of the lintel extends into the channel of the top frame and its rear face 77 is provided with a top flange 78 extending over the flange 65 of the molding.

In Fig. 10 is illustrated a door frame construction designed to be substituted for that shown in Figs. 3 and 7, in the event the front of the cabinet is to be faced with a tile, plaster or other wall surfacing 81. In the latter construction, the lintel, sill, and stiles differ from those illustrated in Figs. 3 and 7, largely in the provision of an adapter frame comprising extensions 82, 83 and 84 which project outwardly from the front face of the cabinet a distance sufficient to accommodate the wall surfacing 81 and to serve as a so-called stop therefor. In addition, the lintel, sill and stile extensions 84 are provided with welded or integral flanges 85 and 86 or their equivalent by which metal or other lath 87 may be attached to the door frame. In the present instance, the wall surfacing comprises tile 88 laid upon a cement bed 89 carried by the metal lath.

The adapter frame is held rigidly in the tile and cement wall surfacing 88 and 89 but is independent of the receptor and cabinet side walls so as to permit the latter to move relatively to the adapter frame and the wall surfacing itself in the event of settlement of the floor on which the cabinet rests. This avoids cracking of the wall surface which would occur (in the event of settlement) if the adapter frame were connected rigidly to the cabinet.

It will be understood that the surfaces of those cabinet walls which are covered by a plaster or other wall surface need not have the enamel finish which is provided for all exposed cabinet surfaces.

As described in greater detail in my co-pending application, Serial No. 103,965, of which the present application is a division, the receptor is advantageously finished in vitreous porcelain enamel to provide a decorative and contrasting effect. In the present instance, a speckle coat of contrasting color is applied in such a way as to fall in large separated drops on the background coat. These spread to irregular and varying areas 94

about $\frac{1}{8}$ of an inch in diameter and smaller and contrast with the background coat 93 to give an attractive finish. The coarse stippling or speckled effect may be produced by lowering the air pressure on the spray gun so that the enamel is deposited in large spaced drops with only a limited number of fine drops. If a uniform or plain color be desired, the finished enamel may be sprayed on the receptor in the usual way. With either method of finish, the coat is dried and subsequently burned at about 1500° F. for about six minutes.

The receptor bottom may advantageously be made slip-proof by embedding in its surface granular material such as fine silica sand which is fused with the enamel coat. In Fig. 9, an attempt has been made to illustrate the sand particles and fine drops of enamel by dots 95, but it should be understood that exact illustration is impossible since the particles of sand are relatively inconspicuous and are individually relatively much smaller than illustrated. It is also difficult to illustrate the relative concentration of the sand particles but preferably the concentration is greater than that illustrated, the effect being more like fine sand paper except that the particles of sand are not as sharp as in sand paper and not quite so concentrated. The application of the sand to the receptor does not render its appearance noticeably different from what it would be had no sand been applied.

Obviously the invention is not limited to the details of the illustrative constructions since these may be variously modified. Moreover, it is not indispensable that all features of the invention be used conjointly, since various features may be used to advantage in different combinations and sub-combinations.

Having described my invention, I claim:

- 40 1. A shower bath cabinet of the character described comprising in combination sheet metal side wall sections, the adjacent side flanges of said sections being spaced apart and a joint strip covering said flanges, a corner strip engaging the opposite faces of said flanges, and a locking device engaging said corner strip and said joint strip, and movable longitudinally relative to both the corner strip and joint strip to draw said strips together to clamp said flanges.
- 45 2. A shower bath cabinet comprising in combination a receptor having side walls provided with an inwardly extending shoulder, side wall sections carried by said receptor side walls, a joint strip covering the adjacent side margins of said sections, and means for holding said joint strip tightly against said flanges, said strip having a projection extending underneath said shoulder to hold said side wall sections against separation from said receptor.
- 50 3. A shower bath cabinet of the character described comprising in combination sheet metal side wall sections, the adjacent side flanges of said sections being spaced apart and a joint strip covering said flanges, a corner strip engaging the opposite faces of said flanges, said corner and joint strips being provided with slots and cam devices projecting into said slots, and a locking strip movable longitudinally in engagement with said cam devices to draw said strips into tight engagement with said flanges.
- 55 4. A shower bath cabinet comprising in combination a receptor having side walls, a horizontal channel strip inside said receptor side walls and carried thereby, plastic sealing material inside the element of said strip, and cab-

inet side wall sections having inwardly offset lower margins seated in said channels, said side sections having portions above said margins projecting inwardly of the latter to overhang the inner face of said channel strip.

5. A shower bath cabinet comprising in combination a receptor having side walls, side wall sections carried by said receptor side walls, a joint strip covering the adjacent side margins of said sections, said strip having a projection in engagement with the receptor to hold the strip when in position against upward movement, and means operative after the strip has been placed in position and without movement of the strip to force the latter into tight engagement with the margin of said side wall sections, thereby holding the latter against upward movement relative to said receptor.

6. A shower bath cabinet of the character de-

scribed comprising in combination spaced sheet metal side wall sections, the adjacent side margins of said sections being inwardly offset relative to the plane of their respective sections to provide inner and outer shoulders at the adjacent offsets, an exterior joint strip covering said margins and lying in the space between said outer shoulders and terminating adjacent thereto, said offset being substantially equivalent to the thickness of said exterior joint strip so that the outer surface thereof is substantially flush with the outer faces of said side wall sections, and an interior joint strip connected with said exterior joint strip and extending behind said inner shoulders to prevent substantially lateral movement of said side wall sections and having portions intermediate its edges lying parallel to the respective offset margins.

PAUL W. KERR.
